R. H. BINNS

FLEXIBLE CLOSURE

Filed Feb. 18, 1925

Fig. 1.

UNITED STATES PATENT OFFICE.

RALPH H. BINNS, OF PITTSBURGH, PENNSYLVANIA, ASSIGNOR OF TWO-SEVENTHS TO
EDWARD H. BINNS.

FLEXIBLE CLOSURE.

Application filed February 18, 1925. Serial No. 10,062.

The present invention relates to improvements in the cam slider for flexible closure of the type shown in application, Serial No. 724,355, filed July 5th, 1924, the present improvements being directed to locking means for securing the slider in the desired position upon the flexible stringers and to the reversible pull member by which the locking means are controlled and the slider conveniently manipulated in either direction upon the stringers.

In order that the invention may be fully understood it will first be described with reference to the accompanying drawings and afterwards pointed out more particularly in the annexed claims.

In said drawings:

Fig. 1 is a front elevation of a portion of a flexible closure embodying the present invention;

Fig. 2 is a similar view with the reversible pull member extended below the slider;

Fig. 3 is a similar view showing the pull member extended above the slider;

Fig. 4 is a vertical sectional view taken on the line 4—4 of Fig. 1;

Figs. 5 and 6 are similar views taken respectively on the lines 5—5 of Fig. 2 and 6—6 of Fig. 3;

Fig. 7 is a transverse sectional view taken on the line 7—7 of Fig. 1;

Fig. 8 is a similar view taken on the line 8—8 of Fig. 3;

Fig. 9 is a transverse sectional view taken on the line 9—9 of Fig. 1 and showing only the fore-plate of the slider and parts carried thereby;

Fig. 10 is a detail underneath view of the reversible pull member detached from the slider.

In the type of flexible closure to which the present invention relates, two flexible strips or stringers 1, 2 are formed at their inner edges with beads or thickened portions 3 upon which are secured interlocking fastening devices.

Each interlocking fastening device is preferably formed with a U-shaped yoke 10 embracing and compressed upon the beaded or thickened edge 3 of a flexible stringer, a narrow neck 12, a forked hook 13, and the opposite riding lugs or shoulders 15. The specific form and operation of the fastening devices of the preferred construction will be

more fully understood by reference to the above named application, Serial No. 724,355.

The operating cam slider is preferably constructed as set forth in above named application of a back-plate 20 and a fore-plate 21 mounted in spaced relation upon a binder 22, with a fastener receiving channel between them. The inner faces of the back-plate and fore-plate are provided with controlling grooves 25 separated by a central guide rib 26. The riding lugs 15 of the fastening devices operate in the controlling grooves 25.

The fore-plate 21 is formed in its outer face with a longitudinal recess 30 in which rests a spring blade 31 secured at its upper end by a rivet 32 seated in the bottom of the recess 30. The lower end of the spring blade 31 is formed with an inwardly presented angular detent 35 which is adapted to be presented over the lower open ends of controlling grooves 25 of fore-plate 21 to thereby intersect the path of the outer riding lugs 15 of the fastening devices. The outward set of the spring blade 31 constituting the supporting arm of the locking detent is such that when unrestrained the detent 35 will be raised above the controlling grooves of the slider fore-plate as shown in Figs. 5, 6 and 8 of the drawings.

The fore-plate 21 is also formed with a guideway 40 above and wider than the recess 30. This guideway 40 is formed by the overhanging longitudinal walls 41 either integral with or otherwise attached to the fore-plate 21. The lock controlling pull member is mounted in the guideway 40 and consists of a blade 45 of spring metal having rolled or turned over finger pieces 46 and 47 at its opposite ends. On each side of the pull member 45 adjacent to the finger pieces 46 and 47 are lateral slots 48 and 49 to receive the inwardly presented guide walls 41 above referred to. These guide walls 41 are presented in parallel relation and, throughout the greater part of their length, they are spaced to correspond with the spacing between the cuts or notches 48 of member 45. At the lower end of the slider these side walls 41 are, however, formed with inwardly extending projections 41^a to produce a narrow throat through which the web between cuts 48, 48 of member 45 cannot pass. These portions 41^a of

tracks 41 thereby constitute a stop for limiting the movement of pull member 45 downwardly upon the slider. This pull member 45 is also designed to project upwardly from the slider and to limit the movement in the upward direction, member 45 is provided with a stud 45^a projecting inwardly near its lower end, which comes in contact with the upper closed end or wall 30^a of recess 30 when the pull member 45 is pulled to its upward limit upon the slider.

As shown especially in Figs. 5 and 6 of the drawings, the pull member 45 has a spring tendency to assume a slight upward bend, so that when pressed into its normal position as represented in Figs. 1 and 4, both ends of member 45 will be confined beneath the flanges 41 and cause the stud 45^a to press upon the spring arm 31 and force the detent 35 into its locking position. In this position it will be understood that the detent 35 will be presented in the path of riding lugs 15 and will engage above a riding lug on one stringer and below a riding lug on an opposite stringer, because of the alternating or zigzag positioning of the fastening devices upon the two stringers. This locking device effectively prevents the movement of the slider upwardly or downwardly upon the interlocked stringers. If it is desired to open the flexible closure, the pull member 45 is moved from the position shown in Figs. 1 and 4 into the position shown in Figs. 2 and 5 with the result that the locking detent 35 will be released and will spring outwardly into unlocked position, and thereby permit the slider to be moved downwardly upon the stringers by the pull of member 45.

When it is desired to close the closure the member 45 is shifted into its position above the slider as shown in Figs. 3 and 6, in which position the locking detent 35 is also released from its locking position, so that the slider is free to respond to the upward pull member 45.

I claim:

1. In a flexible closure or fastener, the combination with flexible stringers carrying spaced interlocking fastening devices, of a fastener operating slider, a locking detent mounted upon said slider in position to engage said fastening devices, and a pull member movably mounted upon said slider and adapted to hold the locking detent in engagement with said fastening devices.

2. In a flexible closure or fastener, the combination with flexible stringers carrying spaced interlocking fastening devices, of a fastener operating slider, a spring detent mounted upon said slider in position to engage said fastening devices, and a detent operating member also mounted upon said slider.

3. In a flexible closure or fastener, the

combination with flexible stringers carrying spaced interlocking fastening devices, of a fastener operating slider, a normally released spring detent mounted upon said slider, and a pull member movably mounted upon said slider and adapted to hold the spring detent in engagement with said fastening devices.

4. In a flexible closure or fastener, the combination with flexible stringers carrying spaced interlocking fastening devices, of a fastener operating slider, a spring detent mounted upon said slider in position to engage said fastening devices, and a spring pull member movably mounted upon said slider and adapted to hold the detent in engagement with said fastening devices.

5. In a flexible closure or fastener, the combination with flexible stringers carrying spaced interlocking fastening devices formed with riding lugs or shoulders, of an operating slider formed with internal controlling grooves engaging said riding lugs or shoulders, a spring arm secured at one end upon said slider, a locking detent upon said spring arm normally supported in released position, and a pull member movably mounted upon said slider and adapted in one position to press the spring supported detent into engagement with said riding lugs.

6. In a flexible closure or fastener, the combination with flexible stringers carrying spaced interlocking fastening devices, of a fastener operating slider, a spring blade carrying a locking detent secured at one end upon said slider and normally supporting the detent in released position, and a pull member movably mounted upon said slider and adapted in one position to press the spring supported detent into engagement with said fastening devices.

7. In a flexible closure or fastener, the combination with flexible stringers carrying spaced interlocking fastening devices, of a fastener operating slider, a normally released spring detent mounted upon said slider, a pull member movably mounted upon said slider and adapted to project either above or below the slider, said pull member arranged to hold the spring detent in locked position in engagement with said fastening devices when the pull member is in intermediate position.

8. In a flexible closure or fastener, the combination with flexible stringers carrying spaced interlocking fastening devices formed with riding lugs or shoulders, of an operating slider formed with internal controlling grooves engaging said riding lugs or shoulders, a normally released spring detent mounted upon said slider, a pull member movably mounted upon said slider and adapted to project either above or below the slider, said pull member arranged to hold the spring detent in locked position in

engagement with said lugs when the pull member is in intermediate position.

9. In a flexible closure or fastener, the combination with flexible stringers carrying spaced interlocking fastening devices formed with riding lugs or shoulders, of an operating slider formed with internal controlling grooves engaging said riding lugs or shoulders, a spring blade secured at one end upon the slider, a detent on the free end of said spring blade adapted to be presented across the path of said riding lugs, a blade-like pull member slidably mounted upon said slider above said spring blade and adapted to be projected either above or below the slider as a pull member and to be placed in an intermediate position to hold the spring detent in locked position.

10. In a flexible closure or fastener, the combination with flexible stringers carrying spaced interlocking fastening devices formed with riding lugs or shoulders, of an operating slider formed with internal controlling grooves engaging said riding lugs or shoulders, said slider being also formed with an external recess, a spring blade seated in said recess and secured therein at one end, a detent formed on the free end of said spring blade adapted to be presented across the path of said riding lugs, a blade-like pull member slidably mounted upon said slider above said spring blade and adapted to be projected either above or below the slider as a pull member and to be placed in an intermediate position to hold the spring detent in locked position.

11. In a flexible closure or fastener, the combination with flexible stringers carrying spaced interlocking fastening devices, of a fastener operating slider having a guideway, a normally released spring detent mounted upon said slider in position to engage said fastening devices, a blade-like pull member mounted in said guideway and carrying a stud adapted to engage said spring detent, and means for limiting the movements of said pull member above and below said slider.

12. In a flexible closure or fastener, the combination with flexible stringers carrying spaced interlocking fastening devices, of a fastener operating slider having an outwardly presented guideway, a normally released spring detent mounted upon said slider adjacent to said guideway in position to engage said fastening devices, a blade-like pull member mounted in said guideway and carrying a stud adapted to engage said spring detent, and means for limiting the movements of said pull member above and below said slider.

13. In a flexible closure or fastener, the combination with flexible stringers carrying spaced interlocking fastening devices formed with riding lugs or shoulders, of an

operating slider formed with internal controlling grooves engaging said riding lugs or shoulders, said slider also having an outwardly presented guideway, a normally released spring detent mounted upon said slider adjacent to said guideway in position to engage said riding lugs, a blade-like pull member mounted in said guideway and carrying a stud adapted to engage said spring detent, and stops upon said guideway for limiting the movement of said pull member above and below said slider.

14. In a flexible closure or fastener, the combination with flexible stringers carrying spaced interlocking fastening devices, of a fastener operating slider, a spring supported locking detent mounted upon said slider in position to engage said fastening devices, and a blade-like pull member formed with finger pieces at its opposite ends movably mounted upon the slider and controlling said detent.

15. In a flexible closure or fastener, the combination with flexible stringers carrying spaced interlocking fastening devices, of a fastener operating slider, a spring supported locking detent mounted upon said slider in position to engage said fastening devices, and a spring metal pull member formed with integral finger pieces at its opposite ends, said pull member being movably mounted upon the slider to project either above or below and controlling said detent.

16. In a flexible closure or fastener, the combination with flexible stringers carrying spaced interlocking fastening devices, of a fastener operating slider formed with a guideway, a spring detent mounted upon said slider in position to engage said fastening devices, a pull member in the form of a blade of spring metal slidably mounted in said guideway and having its opposite ends rolled or coiled into finger pieces, and means for limiting the movements of said pull member above and below the said slider.

17. In a flexible closure or fastener, the combination with flexible stringers carrying spaced interlocking fastening devices, of a fastener operating slider formed with a longitudinal guideway, a spring detent mounted upon said slider in position to engage said fastening devices, a pull member in the form of a blade of spring metal slidably mounted in said guideway and having its opposite ends rolled or coiled into finger pieces and stops upon said pull member and guideway for limiting the movements of said pull member upon said slider.

18. In a flexible closure or fastener, the combination of flexible strips or stringers having spaced interlocking fastening devices, and an operating slider mounted upon said fastening devices, with a blade-like pull member formed with finger pieces at its opposite ends slidably mounted upon said

slider and adapted to project either above or below the slider.

19. In a flexible closure or fastener, the combination of flexible strips or stringers having spaced interlocking fastening devices, and an operating slider mounted upon said fastening devices, with a blade-like pull member slidably mounted upon the slider and having its opposite ends coiled to form integral finger pieces.

20. In a flexible closure or fastener, the combination of flexible strips or stringers having spaced interlocking fastening devices, and an operating slider mounted upon said fastening devices and formed with a guideway, with a pull member in the form of a blade of spring metal slidably mounted in said guideway and having its opposite ends rolled or coiled into finger pieces, and means for limiting the movements of the pull member above and below said slider.

21. A separable fastener slider comprising wings forming diverging channels, a pull device for the slider, a locking tongue separate from said pull device, and means for controlling said tongue from said pull device.

22. The combination with a quick operating fastener comprising opposed series of interlocking elements on the edges of the parts which are to be connected together and an operating member movable along the

series of elements for interlocking and releasing same, of a locking device on the operating member resiliently engaging the interlocking elements for holding the operating member against movement therealong.

23. The combination with a quick operating fastener comprising opposed series of interlocking elements on the edges of the parts which are to be connected together and an operating member movable along the series of elements for interlocking and releasing same, of an arm attached at one end to the operating member and having the other end inturned and adapted to resiliently engage the interlocking elements for holding the operating member against movement therealong.

24. The combination with a quick operating fastener comprising opposed series of interlocking elements on the edges of the parts which are to be connected together and an operating member movable along the series of elements for interlocking and releasing same, of a locking device on the operating member for holding the latter against movement along the interlocking elements, and means on the operating member and relatively movable with respect to said member and the locking device for controlling the operation of the latter.

RALPH H. BINNS.

CERTIFICATE OF CORRECTION.

Patent No. 1,655,982.

Granted January 10, 1928, to

RALPH H. BINNS.

It is hereby certified that the above numbered patent was erroneously issued to the inventor and "Edward H. Binns", as assignee of two-sevenths interest, whereas said "Edward H. Binns, of Pittsburgh, Pa.", should have appeared as assignee of part interest, in said invention, as shown by the records of assignments in this office; and that the said Letters Patent should be read with the correction therein that the same may conform to the record of the case in the Patent Office.

Signed and sealed this 6th day of March, A. D. 1928.

Seal.
